 Kamrath IP Lawfirm, P.A.(57) **CLAIM**

The ornamental design for a handle of a barrow, as shown and described.

DESCRIPTION

FIG. 1 is a perspective view of a handle of a barrow showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view in a condition of use; and,

FIG. 9 is another perspective view shown in an alternate position.

The broken lines in FIGS. 8 and 9 are to show environment and form no part of the claimed design.
